(57) **CLAIM**

The ornamental design for a feeder, as shown and described.

DESCRIPTION

FIG. 1 is a top perspective view of a feeder in accordance with a first embodiment of our new design;

FIG. 2 is a bottom perspective view of the first embodiment;

FIG. 3 is a top view of the first embodiment;

FIG. 4 is a bottom view of the first embodiment;

FIG. 5 is a right side view of the first embodiment;

FIG. 6 is a left side view of the first embodiment;

FIG. 7 is a front view of the first embodiment;

FIG. 8 is a rear view of the first embodiment;

FIG. 9 is an exploded rear perspective view of the first embodiment;

FIG. 10 is a top perspective view of a feeder in accordance with a second embodiment of our new design;

FIG. 11 is a bottom perspective view of the second embodiment;

FIG. 12 is a top view of the second embodiment;

FIG. 13. is a bottom view of the second embodiment;

FIG. 14 is a right side view of the second embodiment;

FIG. 15 is a left side view of the second embodiment;

FIG. 16 is a front view is a of the second embodiment;

FIG. 17 is a rear view is of the second embodiment; and,

FIG. 18 is an exploded top perspective view of the second embodiment.

The broken lines in the drawings illustrate portions of the feeder that form no part of the claimed design.

1 Claim, 18 Drawing Sheets
